DESIGN FOR A PUZZLE

Joseph C. Roch, Providence, R. I.

Application November 21, 1939, Serial No. 88,388

Term of patent 14 years

To all whom it may concern:

Be it known that I, Joseph C. Roch, a citizen of the United States of America, residing at Providence, in the county of Providence and State of Rhode Island, have invented a certain new, original, and ornamental Design for Puzzles, of which the following is a specification, reference being had to the accompanying drawing, forming a part thereof.

Fig. 1 is a front elevation of an assembled puzzle embodying my new design.

Fig. 2 is a front elevation and Fig. 3 is a plan view of one component piece thereof.

Fig. 4 is a front elevation and Fig. 5 is a reverse

plan view of another component piece thereof.

Fig. 6 is a plan view and Fig. 7 is a front elevation of the locking piece thereof.

The puzzle comprises six pieces, three pieces of the type shown in Figs. 2 and 3, two pieces of the type shown in Figs. 4 and 5 and one locking piece as shown in Figs. 6 and 7 assembled together to make up the composite puzzle shown in Fig. 1.

I claim:

The ornamental design for a puzzle, substantially as shown and described.

JOSEPH C. ROCH.
